CARTRIDGE FEEDING MECHANISM FOR MACHINE GUNS

Filed Sept. 16, 1918

Patented July 3, 1923.

1,460,800

UNITED STATES PATENT OFFICE.

MILLARD L. JOHNSTON, OF UTICA, NEW YORK.

CARTRIDGE-FEEDING MECHANISM FOR MACHINE GUNS.

Application filed September 16, 1918. Serial No. 254,217.

To all whom it may concern:

Be it known that I, MILLARD L. JOHNSTON, a citizen of the United States, residing at Utica, in the county of Oneida and State 5 of New York, have invented a certain new and useful Improvement in Cartridge-Feeding Mechanism for Machine Guns, of which the following is a specification, reference being had therein to the accompanying 10 drawing.

My invention relates to a cartridge feeding mechanism for machine guns, and I declare the following to be a full, clear, concise and exact description thereof sufficient 15 to enable anyone skilled in the art to which it appertains to make and use the same, reference being had to the accompanying drawings in which like reference characters refer to like parts throughout the specification.

20 The object of the invention is to provide a simple device that will revolve the cartridge carrier of an automatic machine gun in such a manner as to bring successively the cartridges into loading position. Sufficient 25 parts of a machine gun to which the invention is applied are herein illustrated for the purpose of comprehending it.

The object will be understood by referring to the drawings, in which:

30 Fig. 1 is a vertical section of a machine gun, showing parts broken away, and the invention assembled thereto;

Fig. 2 is an enlarged perspective view of the cartridge carrier employed;

35 Fig. 3 is an enlarged perspective view of the latch carrier actuator, the latch thereof having been removed;

Fig. 4 is an enlarged view on the scale of Fig. 3, showing a perspective view of the 40 pawl and spring attached, which are used;

Fig. 5 is a plan view looking from beneath upward of the latch carrier actuator;

Fig. 6 is an enlarged view on the scale of Fig. 3, showing a side elevation of the pawl 45 and spring attached.

Referring more particularly to the drawings, the invention embodies a hollow cylinder —1— to which is formed in an integral manner a depending wall 2. The lower portion 50 of the wall 2 supports two plates 3 and 4, also formed integral with the wall 2. A chamber 5 for the mounting of a pawl or latch 6 is provided between the plates 3 and 4. Each of the plates 3 and 4 has a cut or 55 narrow recess 7—7 with open ends. These recesses 7 extend a short distance into the

wall 2 to form a bearing for the studs or shafts 8—8 that are mounted to extend from either side of the pawl 6.

The pawl 6 is equipped with a slot at 10 60 which slot extends around the end 11 and is adapted for housing the end of a spring 12. The extreme end 13 of the spring 12 is secured in a hole 50 formed at an angle to the end of the slot 10 and the other or free end 65 of the spring 12 extends outward from the rear surface of the pawl 6 and rests when the pawl 6 is assembled within the chamber 5, formed between the plates 3 and 4, against the adjacent surface of the wall 2, whereby 70 to force the end 14 of the pawl 6 normally outward upon the studs or shafts 8—8 as a fulcrum. The pawl 6 is held within the chamber 5, however, when the parts are assembled, by the adjacent wall of a chamber 75 formed within the part 9 of the receiver 51. The shank 15 of the pawl 6 can be pushed within the chamber 5, against the tension of the spring 12, whereby the surface 16 of the end 14 will align with the edges 17—18 of 80 the plates 3 and 4 respectively.

In operation, the invention is mounted to an automatic machine gun 20 in such manner that the hollow cylinder —1— is located within the carrier tube 22 thereof. The 85 actuator shaft 23 projects loosely through the aperture 24 of the hollow cylinder —1— and permits the cylinder —1— to slide along the shaft 23. The lower surface of the tube 22 has an elongated recess 35 for the projection and horizontal motion of the wall 2. When the gun is discharged, a part of the 90 gases of explosion expand through the passageway 25 communicating with the bore 26 of the barrel 27, thereby leading the gases 95 to the gas chamber aligning with the tube 22. The gases expand further through the spiral channel 28 of the gas delay and finally reach the head 29 of the piston. The piston is forced, thereby, rearwardly to carry the 100 breech bolt 30 backward. Immediately the extractors 31—31 of the breech bolt 30 clear the channels 32 formed between the flanges or ribs 33 of the cartridge carrier, the shoulder 36 mounted to move with the actuator 105 shaft 23 will strike the contiguous edge of the hollow cylinder —1— and force the same together with its connected parts, including the pawl 6, towards the rear. Immediately the pawl 6 begins to move toward the rear 110 and out of the chamber in part 9 of the receiver 51, the head 14 thereof will spring to

the right, if looking in a direction indicated by standing at the breech and facing the muzzle, whereby the beveled side 36^a of said head 14 will slide past the beveled edge 37 of 5 the adjacent rib 33 and be in position to enter the next succeeding channel 32 to the right of said carrier and, as it progresses into said channel 32 it will cause said carrier to rotate through a given arc to effect 10 an alignment of the channel 32 between the contiguous flanges 33 with the edges 17 and 18 of the plates 3 and 4 respectively. The flanges or ribs 33 are reduced a given distance at 40—40 on either side to allow for a 15 limited projection of the head 14 of the pawl 6 and the adjacent portions of the plates 3 and 4.

This rotation of the cartridge carrier is adapted to place a cartridge into loading 20 position, so that when the breech bolt 30 again goes forward under the tension of the coiled spring 41, the shoulder 42 of the sleeve 43, which is integral with and moves with the member 44 for actuating the breech 25 bolt 30, will make contact with the adjacent edge of the hollow cylinder —1— and force the same together with its connected parts, including the pawl 6, to original position illustrated by dotted lines in Fig. 1. It will 30 be noted that the shoulder 36 and the shoulder 42 do not make contact with the respective edges of the hollow cylinder —1—, until near the limiting position of their respective motions, whereby the resultant motion of 35 the sleeve —1— and pawl 6 is comparatively small, although sufficient to effect the desired function of those parts.

Immediately the pawl 6 clears the channel 32, on the return motion of the shaft 23, 40 it will be forced against the pressure of the spring 12, within the chamber in part 9 of the receiver 51, whereby said head 14 of the pawl 6 will be ready to spring again towards the left to enter the next succeeding channel 45 32 to the left of the carrier, when the latch carrier again moves towards the rear.

The sides of the breech bolt 30 taper towards the bottom to fit into corresponding recesses in the receiver portion 51 of the

machine gun, whereby to hold the breech 50 bolt 30 in vertical position and so that it can slide horizontally.

Having thus described my invention what I claim as new and desire to secure by Letters Patent is:

1. In a machine gun having a cartridge carrier, a latch carrier, a demountable latch in said carrier, spring means for actuating said latch laterally, and means for periodically striking the latch carrier, whereby to 60 revolve the cartridge carrier to bring the cartridges into loading position.

2. In a machine gun having a cartridge carrier, a latch carrier, a demountable latch mounted in said carrier, automatic means for 65 actuating said latch laterally, and means for impinging against said latch carrier, whereby to actuate said latch in a longitudinal manner to revolve the cartridge carrier to bring the cartridges into loading position. 70

3. In a machine gun having a cartridge carrier with beveled sides, a demountable latch carrier, a latch having a beveled edge adapted to make contact with said beveled edges of the carrier, a spring for actuating 75 said latch laterally, whereby to engage the beveled edge thereof successively with the beveled edges of the carrier, and automatic means for actuating said latch longitudinally, whereby to revolve said cartridge carrier to bring the cartridges into loading position. 80

4. In a machine gun having a cartridge carrier, beveled edges on said carrier, a latch carrier, a latch carried by said latch carrier, a beveled edge on said latch, an open recess in said latch carrier, whereby to demountably hold said latch in a pivotal manner, a spring for turning said latch upon its pivot, and means for periodically impinging 90 against said latch carrier, whereby to move said latch longitudinally to rotate said cartridge carrier to bring the cartridges into loading position.

In testimony whereof I have affixed my 95 signature.

MILLARD L. JOHNSTON.
